Application August 21, 1941, Serial No. 407,745

11 Claims. (Cl. 62—5)

This invention relates to refrigeration, and more particularly to refrigeration apparatus of the kind operated by heat.

In absorption refrigeration apparatus of the kind described in application Serial No. 350,239 of Albert R. Thomas, a generator or heat receiving part is provided with a jacket forming a chamber which is vented to atmosphere and within which are disposed a plurality of vertical tubes or risers. Steam is supplied from a boiler to the chamber so that substantially full length heating of the tubes may be effected, whereby absorption liquid therein is heated to cause expulsion of refrigerant vapor and also effect lifting or raising of liquid to a higher level by gas or vapor-lift action.

The steam supplied to the generator chamber condenses therein and collects in the bottom of the chamber. In many instances, because of space requirements, the condensate is collected at a region below the liquid level in the steam boiler so that provision must be made for returning liquid condensate to the boiler.

It is an object of the invention to provide an improved condensate return pump which is extremely quiet in operation to lift or raise condensate formed in the generator so that the raised condensate can flow to the boiler.

Another object of the invention is to provide an improvement for utilizing warm condensate to shut off the heat supply to the steam boiler in the event the condensate return pump is rendered inoperative to return condensate from the generator to the steam boiler.

A further object of the invention is to provide an improvement for returning condensate to the boiler in such a manner that a single expansible fluid thermostat can be utilized to shut off the heat supply to the steam boiler with rise of temperature occasioned either by passing of steam through the vent in the generator chamber or operating failure of the condensate return pump.

The invention, together with the above and other objects and advantages thereof, will be better understood from the following description taken in conjunction with the accompanying drawings forming a part of this specification, and of which:

Fig. 1 illustrates more or less diagrammatically refrigeration apparatus and a heating system therefor provided with a condensate return pump embodying the invention;

Fig. 2 is a view in elevation, partly broken away, illustrating more clearly the condensate return pump shown in Fig. 1;

Fig. 3 is a vertical sectional view taken on line 3—3 of Fig. 2; and

Fig. 4 is a horizontal sectional view taken at line 4—4 of Fig. 2.

Referring to Fig. 1, the invention is shown in connection with refrigeration apparatus of an absorption type like that described in the aforementioned Thomas application. A system of this type operates at low pressures and includes a generator 10, a condenser 11, an evaporator 12, and an absorber 14 which are interconnected in such a manner that the pressure differential in the apparatus is maintained by liquid columns.

The generator 10 includes an outer shell 15 within which are disposed a plurality of vertical riser tubes 16 having the lower ends thereof communicating with a space 17 and the upper ends thereof extending into and above the bottom of a vessel 18. The space 19 within shell 15 and about the tubes 16 forms a steam chamber to which steam is supplied through a conduit 20 from a steam boiler 21.

The boiler 21 is provided with fire or heating tube 22 into the lower end of which is adapted to project the flame produced by a burner 23. A combustible gas is delivered from a source of supply through a conduit 24 in which is connected an electro-magnetically operated solenoid valve 25 connected by conductors 26 and 27 to a suitable source of electrical energy. While only a single heating tube and burner are illustrated a number of heating tubes and burners may be employed with the upper end of each tube connected to a flue or riser 28. The water in boiler 21 is heated by the hot gases passing through the heating tubes 22, thereby producing steam which flows through conduit 20 to generator 10.

The space 19 provides for full length heating of riser tubes 16 with a vent 30 provided at the upper end of shell 15 through which steam can flow into the atmosphere. Condensate formed in steam chamber 19 is returned to boiler 21 through a conduit 31, a condensate return pump 32 to be described presently, and a conduit 33.

The heating of riser tubes 16 in generator 10 by the steam causes refrigerant vapor to be expelled from absorber, such expelled vapor being effective to raise liquid absorber by gas or vapor-lift action. The expelled vapor passes from the upper ends of the riser tubes into vessel 18, and thence flows through a conduit 34 into condenser 11 in which the expelled vapor is liquefied. The liquid refrigerant formed in condenser 11 flows through a conduit 35 into the upper part of evaporator 12. The refrigerant evaporates in

evaporator 12 with consequent absorption of heat to produce a refrigerating effect which may be utilized to cool air flowing through a duct 36 indicated in dotted lines.

The refrigerant vapor formed in evaporator 12 flows therefrom to an absorber 14 in which the vapor is absorbed into a liquid absorbent, such as lithium chloride solution, for example, which enters the upper part of the absorber through a conduit 37. The absorption liquid enriched in refrigerant is conducted from absorber 14 through conduit 38, a first passage in liquid heat exchanger 39, conduit 40, vessel 41, and conduit 42 into space 17 of generator 10. Refrigerant vapor is expelled out of solution in generator 10 by heating, and the solution is raised by gas or vapor lift action in riser tubes 16, as explained above.

The absorption liquid in vessel 18 is deprived of refrigerant since refrigerant vapor has been expelled therefrom in generator 10. The absorption liquid in vessel 18 flows therefrom through conduit 43, a second passage in liquid heat exchanger 39 and conduit 37 into the upper part of absorber 14. This circulation of absorption liquid results from the raising of liquid in riser tubes 16, whereby the liquid can flow to absorber 14 and return from the latter to generator 10 by force of gravity.

The upper part of vessel 41 and vessel 18 are connected by a conduit 48, so that the pressure in the vessel is equalized with the pressure in the upper part of generator 10 and condenser 11. The absorber 14 and condenser 11 constitute heat rejecting parts of the refrigeration apparatus and are cooled by a suitable cooling medium, such as water, for example, which is conducted from a suitable source of supply through a conduit 44 to a bank of tubes 45 within the absorber whereby heat of absorption is given up to the cooling water. The cooling water is conducted from absorber 14 through a conduit 46 to condenser 11 in which heat of condensation is given up to the cooling water, the cooling water thence leaving the condenser through a conduit 47.

In order to simplify the drawings the parts of the refrigeration apparatus have not been shown in detail, such an illustration of the parts not being necessary for an understanding of this invention. The disclosure in the aforementioned Thomas application may be considered as being incorporated in this application and, if desired, reference may be made thereto for a detailed description of the refrigeration apparatus.

In order to keep the overall height of the refrigeration apparatus and heating system to a minimum, the bottom part of the generator 10 is below the surface level of water maintained in boiler 21. Under these conditions provision must be made for lifting or raising condensate formed in generator 10, so that the raised condensate can flow to the boiler.

In accordance with this invention, therefore, a condensate return pump 32 is connected in the condensate return line including conduits 31 and 33. The pump 32 comprises an outer shell 50 having a bottom 51 and a top 52. Integrally with the top 52 are formed a downwardly depending sleeve 53 and reinforcing ribs 54 therefor. The lower end of sleeve 53 is enlarged at 55 to form a recess adapted to receive a rotatable impeller 56. The impeller 56 is multi-bladed, as shown most clearly in Figs. 3 and 4, and is secured to the lower end of a shaft 57 which extends upwardly through sleeve 53. The shaft 57

57 is carried by a rotor of an electric motor 58 in which the rotor is journaled in any suitable manner. The electric motor 58 is secured to the top 52 and provided with a connection 59 for connecting the motor to a source of electrical energy.

To the enlarged part 55 at the lower end of sleeve 53 is secured a plate 60 to form a chamber 61 in which the impeller 56 is adapted to rotate. 10 The plate 60 is formed with a central opening 62 about which is formed a depending flange or lip 63. At the outer peripheral edge of plate 60 is formed an annular skirt or flange 64 of greater depth than lip 63 and to which is secured a suitable screen 65 to prevent foreign matter from entering the pump chamber 61.

During operation of the pump 32 the warm condensate flows by gravity from the bottom part of generator chamber 19 through conduit 20 31 into the bottom part of shell 50. The condensate passes through the opening 62 in plate 60 into chamber 61 in which the velocity of the liquid is increased by the impeller 56, the velocity being converted into pressure by the chamber to cause raising or lifting of liquid through a riser tube 66 which is connected at its lower end to the outer peripheral part of chamber 61. The riser tube 66 is located within shell 50 with the upper end thereof terminating 25 in a flanged opening 67 formed in the top 52. The flanged opening 67 is threaded to receive one end of conduit 33 through which the raised condensate flows to boiler 21.

The condensate return pump 32 is especially 35 quiet in operation due to the provision of lip 63 which extends downwardly from the inlet opening 62 of chamber 61 into the pocket formed by the skirt or flange 64. With the pump operating to lift condensate through tube 66, the 40 lip 63 serves to confine the noise produced by the pump that otherwise would be quite noticeable.

In the event the condensate return pump 32 fails to operate, it is desirable to shut off the 45 heat supply to the boiler 21. This is accomplished by providing pump 32 with an overflow tube 68 into the upper part of which condensate can overflow from shell 50 through a connection 69. To the bottom part of tube 68 is connected 50 an overflow tube 70 through which condensate flows to waste.

In the bottom part of tube 68 is disposed a bulb 71 of an expansible fluid thermostat. The 55 expansible fluid thermostat is charged with a suitable volatile fluid and includes the bulb 71, an expansible and contractible bellows 72 arranged in a casing 73, and a capillary tube 74 connecting the bulb 71 and bellows 72. The bellows 72 is arranged to operate a suitable switch 75 which is mounted in casing 73 and connected in conductor 26. The expansible fluid thermostat and switch 76 associated therewith are fully described in my application Serial No. 407,746 filed August 21, 1941, and have not been shown 60 in detail in the drawings since a complete illustration of these parts is not necessary for an understanding of the present invention. When reference is made to my co-pending application it will readily be understood that switch 75 is 65 of the manual reset type and, when closed, completes an electrical circuit for solenoid valve 25 to energize and open the latter so that gas can flow through conduit 24 to burner 23.

In the event pump 32 fails to operate, the liquid level rises in shell 50 until condensate over-

flows through connection 69 into tube 68. The warm condensate flowing over the surface of bulb 71 heats the latter to cause the pressure of the volatile fluid in the expansible fluid thermostat to increase. When the pressure in the expansible fluid thermostat increases due to heating of bulb 71, the expansible bellows 72 expands sufficiently to cause switch 75 to open and break the circuit for solenoid valve 25, whereby the latter closes to shut off flow of gas to burner 23 and hence shut off the heat supply to the burner.

It is also desirable to shut off the heat supply to burner 21 in the event steam flows from generator chamber 19 through vent 30 into the atmosphere. This may occur, for example, when circulation of air past cooling element 12 is not effected and there is loss of load on the latter. In order that a single expansible fluid thermostat can be employed to shut off the heat supply either when steam flows through vent 30 or pump 32 fails to return condensate from generator chamber 19 to boiler 21, a second thermal bulb 76 is connected in capillary tube 74. The bulb 76 is located in vent 30 and becomes heated when steam flows through the vent into the atmosphere. With heating of bulb 76 the pressure of the volatile fluid in the expansible fluid thermostat increases to cause opening of switch 75, in the manner explained above when bulb 71 becomes heated.

Since the generator chamber 19 is vented to atmosphere, the heating system operates substantially at atmospheric pressure with the steam being at a temperature of approximately 212° F. when it flows through vent 30. The temperature of the warm condensate, on the other hand, may be approximately 160° F. when it overflows into tube 68 in the event pump 32 fails to operate. In order to make certain that switch 75 will not open inadvertently on occasions when there is slight breathing in vent 30, that is, a slight amount of steam passing through the vent to atmosphere alternating with a slight amount of air flowing into generator chamber 19, it is desirable to provide an expansible fluid thermostat which will be effective to open switch 75 when the temperature is relatively high and in the neighborhood of 160° F. Since this is a relatively high temperature at which to operate switch 75 with the warm condensate, the parts have been arranged in such a manner that efficient heat transfer from the condensate to bulb 71 is obtained in the event pump 32 fails to operate. For this reason the bulb 71 is arranged below the connection 69 so that the condensate flows over the entire exterior surface of the bulb to obtain efficient heat transfer. This arrangement is also advantageous in that the warmest condensate is employed at the instant that overflow occurs. By providing the raised overflow tube 70 and causing warm condensate to flow over the surfaces of tube 68, the cold metal of the tube is heated very rapidly.

In addition to the control described, a normal control is usually provided for controlling the fuel supply to the burner 23 or a plurality of such burners, so that the rate at which steam is supplied to generator steam chamber 19 can be controlled. The normal control is generally operative responsive to a temperature condition affected by the cooling element and may be of the character described in my application Serial No. 406,777 filed August 14, 1941, in which sequential control of a plurality of burners is effected.

The normal control may include switches which

are also connected in the circuit of the solenoid valve 25 so that, when an adverse operating condition occurs which causes flow of steam through the vent 30 or overflow of warm condensate into tube 68, the control described above will open the circuit of the solenoid valve to shut off flow of fuel to the burner or burners. When the adverse operating condition is corrected and steam no longer flows through the vent 30 or warm condensate does not overflow into tube 68, the switch 75 can be manually closed to complete the circuit for the solenoid valve 25 so that the above-described normal control of the burner 23 may be resumed to control the rate at which heat is supplied to boiler 21.

In view of the foregoing, it will now be understood that an improved condensate return pump 32 has been provided which is extremely quiet in operation. Moreover, the parts of the pump are so located and arranged with respect to each other that the warm condensate can be effectively utilized to shut off the heat supply to the steam boiler 21 in the event that the pump fails to operate.

Although a single embodiment of the invention has been shown and described, it will be apparent that modifications and changes can readily be made without departing from the spirit and scope of the invention, as pointed out in the following claims.

30 What is claimed is:

1. In refrigeration apparatus, a generator, a steam boiler, a heater for supplying heat to said boiler, a conduit to conduct steam from said boiler to said generator to effect heating of the latter, a pump for raising to a higher level condensate formed at said generator, a conduit for conducting the raised condensate to said boiler, and a control for controlling said heater to reduce the heat supplied by said heater to said boiler when said pump becomes ineffective to raise condensate to said higher level at a sufficiently rapid rate.

2. In refrigeration apparatus, a generator, a steam boiler, a heater for said boiler, a conduit to conduct steam from said boiler to said generator to effect heating of the latter, a pump for raising to a higher level condensate formed at said generator, a conduit for conducting the raised condensate to said boiler, and a control responsive to warm condensate formed at said generator for controlling said heater.

3. In refrigeration apparatus, a generator provided with a steam chamber having a condensate drain connection and a vent to atmosphere, a steam boiler, a conduit to conduct steam from said boiler to said generator to effect heating of the latter, a pump including a movable element for raising to a higher level condensate formed in said chamber, and a conduit for conducting the raised condensate to said boiler, said vent and condensate drain connection being so constructed and arranged that, even when a liquid seal is formed in said drain connection by condensate passing therein from said chamber, excess steam can pass from said chamber through said vent into the atmosphere and air can pass from the atmosphere through said vent into said chamber when the latter is not completely filled with steam.

4. In refrigeration apparatus, a generator, a steam boiler, a heater for said boiler, a conduit to conduct steam from said boiler to said generator to effect heating of the latter, a pump for raising to a higher level condensate formed at said generator, a conduit for conducting the raised

condensate to said boiler, a well into which warm condensate overflows when said pump fails to operate, and a thermostat control including a part located in said well and arranged to be heated by overflow condensate for controlling said heater.

5. In refrigeration apparatus, a heat receiving part, a steam boiler, a gas burner for heating said boiler, an electrically-operated valve for controlling flow of gas to said burner, a conduit to conduct steam from said boiler to said heat receiving part to effect heating of the latter, a pump for raising to a higher level condensate formed at said heat receiving part, a conduit for conducting the raised condensate to said boiler, and a control including a portion arranged to be heated by condensate formed at said heat receiving part for controlling said electrically-operated valve.

6. In refrigeration apparatus, a heat receiving part, a source of steam, a conduit to conduct steam from said source to said heat receiving part to effect heating of the latter, structure for controlling flow of steam from said source to said heat receiving part, a pump for raising to a higher level condensate formed at said heat receiving part, and a control for said structure operable when said pump becomes ineffective to raise condensate to the higher level at a sufficiently rapid rate.

7. In refrigeration apparatus, a heat receiving part, a source of steam, a conduit to conduct steam from said source to said heat receiving part, and a pump for raising to a higher level condensate formed at said heat receiving part, said pump including a casing having an inlet for the warm condensate, structure within said casing providing a chamber and a rotatable impeller therein, the bottom wall of said chamber having an opening through which condensate passes into said chamber, and a riser tube communicating with said chamber and through which condensate is raised to the higher level, said structure including a skirt extending downwardly from the bottom wall of said chamber to form a pocket, and a lip about said opening extending downwardly into said pocket.

8. In refrigeration apparatus, a heat receiving part, a source of steam, a conduit for conducting steam from said source to said heat receiving part, a device for controlling flow of steam from said source to said heat receiving part, structure including a pump for raising to a higher level condensate formed at said heat receiving part, a well associated with said structure and into which warm condensate overflows when said pump fails to operate, and an expansible fluid thermostat

for controlling said device, said expansible fluid thermostat including a thermal bulb located in said well and adapted to be heated by condensate overflowing therein.

5. 9. In refrigeration apparatus, a heat receiving part provided with a chamber, a steam boiler, a heater for supplying heat to said boiler, a conduit to conduct steam from said boiler to said chamber to effect heating of said heat receiving part, the bottom part of said chamber being below the surface level of water maintained in said boiler, structure for returning to said boiler condensate formed in said chamber and collecting in the bottom part thereof, said structure including a pump for raising condensate from one level to a higher level, and a device operable to reduce the rate at which said heater supplies heat to said boiler, said device being operable responsive to a condition produced as a result of said pump becoming ineffective to raise liquid from said one level to said higher level at a sufficiently rapid rate.

10. 10. In refrigeration apparatus, a heat receiving part provided with a chamber, a steam boiler, a heater for supplying heat to said boiler, a conduit to conduct steam from said boiler to said chamber to effect heating of said heat receiving part, the bottom part of said chamber being below the surface level of water maintained in said boiler, structure for returning to said boiler condensate formed in said chamber and collecting in the bottom part thereof, said structure including a pump for raising condensate from one level to a higher level, and a device operable to reduce the rate at which said heater supplies heat to said boiler, said device being operable responsive to a rise in temperature affected by warm condensate when said pump becomes ineffective to raise condensate from said one level to said higher level at a sufficiently rapid rate.

15. 11. In refrigeration apparatus a generator, a steam boiler, a conduit to conduct steam from said boiler to said generator to effect heating of the latter, a pump connected to said generator for raising condensate formed in said generator to a higher level, and a conduit for conducting raised condensate to said boiler, said pump comprising a casing forming a chamber, a rotatable impeller in said chamber, said casing having an opening forming an inlet through which the condensate enters said chamber, and means forming a pocket adjacent the inlet and in communication therewith and the condensate flowing to the chamber for confining and muffling noise produced during operation of said pump.

SVEN W. E. ANDERSSON.
